SPONGE MOP AND COMPRESSING APPARATUS THEREFOR

Rice B. Arnold, Parkville, Mo.

Application November 5, 1956, Serial No. 620,398

4 Claims. (Cl. 15—119)

This invention relates to mops, and more particularly to sponge mops of the type adapted for manual use in cleaning and waxing floors, cleaning ceilings, walls and the like.

The principal object of the present invention is to provide a mop of sponge rubber or plastic material consisting of very small pores for the retention of the maximum amount of water and to have the maximum amount of resiliency, and means for exuding water and soap therefrom by a pair of elements carried by the frame of the mop whereby the water and soap may be removed from the sponge without involving contact of the hands with the soapy water.

Other objects of the present invention are to provide a cellular, resilient, hygroscopic sponge cleaning element for the wiping member of the mop having two sections secured together by a plate with adhesive and the plate having bearing elements or shafts for a wire frame for the handle; to provide a hinged bearing member on one leg of the frame for engaging the shaft on the plate without bending the wire frame; to provide for fastening the handle to the bars of the wire frame; to provide spring tension means on the wire frame and plate so that when the sponge element is raised from the surface it will automatically align with the frame of the handle; to provide clamping elements hingedly connected to the wire frame and spring urged to lie on either side of the handle and adapted to be rotated on the wire frame to squeeze the cellular sponge element therebetween to exude the water and soap therefrom and, upon release of the handle of the clamping elements they will be returned to position alongside the handle; to provide hook means for holding the clamping elements to the handle; and to provide a device of this character simple and economical to manufacture.

In accomplishing these and other objects of the invention, I have provided improved details of structure the preferred forms of which are illustrated in the accompanying drawings, wherein:

Fig. 1 is a perspective, partly fragmentary view illustrating the mop and handle therefor embodying the features of my invention.

Fig. 2 is a cross-sectional view thereof, taken on a line 2—2, Fig. 1.

Fig. 3 is a cross-sectional view illustrating the clamping elements engaging the cellular sponge for squeezing the same.

Fig. 4 is an enlarged sectional view of the hinged bearing on the end of one leg of the frame, taken on a line 4—4, Fig. 1.

Fig. 5 is an enlarged side view showing the spring means on the other leg of the frame.

Fig. 6 is an enlarged fragmentary view of the handle ends of the clamping members and the hooks on the handle for securing the same to the handle during mopping operation.

Referring more in detail to the drawings:

1 designates a mop embodying the features of my

2

invention comprising a cellular sponge element 2 having two sections 3 and 4. A plate 5 of metal, plastic or the like, is secured between the two sections of cellular material by adhesive or the like as indicated at 6.

5 Each side edge of the plate member 5 is provided with shafts or bearing members 7 and 8 for receiving the lower ends 9 and 10 of the legs 11 and 12 of a wire frame 13. The frame comprises a pair of spaced bars 14 and 15 connecting the legs 11 and 12 as at 16. The leg members 11 and 12 and bars 14 and 15 form the substantially rectangular shaped frame 13 which will clear the mop element so that the said element will rotate within the frame. A spring 17 is secured to the leg member 12 and has one end secured in a suitable manner to the side edge of the plate 5 as illustrated at 18 (Fig. 1) for exerting tension on the cellular sponge element so that when the element is raised from the floor surface or other surface the spring will cause the sponge to move into axial alignment with the legs 11 and 12.

15 The end 10 of the leg 12 comprises an eye 19 (Fig. 5) adapted to engage over the shaft 8 to provide a rotatable mounting for one side of the sponge element 2 adjoining the leg 12. A washer 20 is provided between the eye 19 and plate 5 for a smooth rotation of said sponge element 2. The lower end 9 of the leg 11 is provided with a fork-like portion 21 (Fig. 4) for an easy inserting of the shaft or bearing member 7. The open end 22 of the fork portion 21 is closed by a hinge member 23 which has one side pivotally connected to one side of the fork portion 21 as indicated at 24 in Fig. 4. Welded or otherwise suitably secured to the other side of the fork portion or slightly above thereof is a keeper 25 adapted to receive the upper end of the hinge member 23 thus forming an eye similar to the eye on leg 12. A washer 26 is engaged over the shaft 7 between the plate 5 and the end 9 of the leg 11 and an annular shoulder or stop 27 is provided on the outer side of the shaft 7 to prevent disengaging of the end 9 from the shaft 7 after the fork-like portion 21 and hinge member 23 are engaged around the shaft 7 between washer 26 and shoulder 27 and the hinge member is locked within the keeper 25.

25 Hingedly connected to the bars 14 and 15 as at 28 and 29 are clamping elements 30 and 31 which may be made of metal, plastic or the like which are rotatable on the bars 14 and 15 for squeezing the cellular sponge element between the outer surfaces thereof as later shown.

30 32 designates a handle for operating the mop and includes a metal member or ferrule 33 at its lower end which is rigidly secured to and between the bars 14 and 15 at substantially the center thereof by welding or other suitable means as indicated at 34 (Fig. 1).

35 The clamping elements are adapted to lie alongside the handle 32 and when not in use are held thereto by hook members 35 and 36 secured to the handle 32 and said hook members extend through openings 37 and 38 in the handles 39 and 40 extending outwardly and downwardly in overlying relation to the outer surfaces of the clamping elements 30 and 31.

40 Spring members 41 and 42 are provided for engagement of the bars 14 and 15 and the outer surfaces of the plate portions 43 and 44 of the clamping elements 30 and 31 to exert tension on the clamping elements to tend to urge them toward the handle member 32 when not in use. Each spring is sleeved on one bar with a portion thereof sleeved on the other bar, and has the respective ends engaging the outer surfaces of the respective clamping elements.

45 In operation of the device the frame 13 is easily at-

tached to the sponge element 2 by first placing the eye 19 over the shaft 8 and the end 9 having a hinged portion may then be attached to the shaft 7 by loosening of the hinge member 23 from the keeper 25 then after the fork portion 21 is engaged over the shaft 7, between washer 26 and shoulder 27, the hinge member 23 is returned to be locked in the keeper 25. Then the mop is in operative position as shown in Fig. 1 and may be inserted in a container of soapy water or other material for cleaning the surface of the floor or walls and the like and when it is desired to remove the soap and water and dirt from the sponge element the handles 39 and 40 are grasped by the user and disengaged from the hook or lock members 35 and 36 and the clamping members 30 and 31 are rotated on the bars 14 and 15 to clamp the sponge element 2 therebetween (Fig. 3) and pressure exerted thereon will remove the water and soap therefrom. When the sponge element is removed from the floor it will move in axial alignment with the frame legs 11 and 12 due to the action of the spring 17 on leg 12 and it is a relatively simple matter to move the clamping members 30 and 31 to contact the sponge element and retain it therebetween during the squeezing operation.

It will be obvious from the foregoing that other types of cleaning elements may be used in place of the cellular sponge element such as a brush or a cloth or string cleaning element, as I do not wish to be limited to any particular type of cleaning element proper.

It will be further obvious from the foregoing that I have provided an improved mop head and handle element with clamping members thereon which may be utilized for squeezing water and soap from the cleaning element with ease and comfort.

What I claim and desire to secure by Letters Patent is:

1. A mop of the character described comprising, an absorbent compressible element in the form of a block having opposed side faces substantially parallel to each other, outwardly extending shafts secured in the respective side faces of said absorbent compressible element, a frame member having a pair of legs with bearings on the ends thereof engaging said shafts for swinging movement of said absorbent compressible element on said frame member, one of said shafts having an annular shoulder on its outer end, one of the bearings including a forked portion of the leg adapted to engage said one of said shafts and having a hinge member with one end pivotally connected to one side of the forked portion with means for securing the other end to the other side of the forked portion whereby the bearing is removably mounted in said shaft, said frame having bars connecting said legs and extending parallel with the shafts, a handle rigidly secured to said bars, means on one of said legs and engaging said absorbent compressible element for retaining said element in parallel relation with the legs of the frame when said element is not in contact with the surface to be cleaned, a pair of clamping members rotatably secured to said bars for movement around said absorbent compressible element to compress the same, and spring means for urging the clamping members toward said handle when the compressing action is completed.

2. A mop of the character described comprising, an absorbent compressible element in the form of a block having opposed side faces substantially parallel to each other made of two pieces of sponge rubber, a plate member between said pieces having side edges, means for securing said pieces to said plate member, short shafts secured to the respective side edges of said plate member, a frame of substantially rectangular shape including a pair of rod members having one end bent to pivotally engage said shafts and having bars connecting said rods and extending parallel with the shafts, said frame being of a size to extend beyond the forward and rear portion of the absorbent compressible element, a handle rigidly secured to said bars, a spring sleeved on one of said

rods and one end thereof engaging the absorbent compressible element for retaining said element in parallel relation with the legs of the rod members of the frame when said element is not in contact with the surface to be cleaned, and a pair of clamping members rotatably secured to said bar portion of the frame for movement around said absorbent compressible element to compress the same.

3. A mop of the character described comprising, an absorbent compressible element in the form of a block having opposed side faces substantially parallel with each other made of two pieces of sponge rubber, a plate member between said pieces having side edges, means for securing said pieces to said plate member, short shafts secured to the respective side edges of said plate member, a frame of substantially rectangular shape including a pair of rod members having one end bent to pivotally engage said shafts, a pair of bars spaced horizontally apart connecting said rods and extending parallel with the shafts, said frame being of a size to extend beyond the forward and rear portion of the absorbent compressible element, a handle rigidly secured to said bars, means on said frame and engaging the absorbent compressible element for retaining said element in parallel relation with the legs of the rod members of the frame when said element is not in contact with the surface to be cleaned, a clamping member rotatably secured to each of said bars for movement away from said handle and around said absorbent compressible element to compress the same between the outer surfaces of said members to remove the liquid therefrom, and a spring member sleeved on one bar and a portion thereof sleeved on the other bar with the respective ends thereof engaging the outer surface of the respective clamping members for urging the clamping members toward said handle when the compressing action is completed.

4. A device of the character described comprising an absorbent compressible element of substantially rectangular shape made of two pieces of sponge rubber, a plate member between said pieces having side edges, means for securing said pieces to said plate member, short shafts secured to the respective side edges of said plate member and extending outwardly from said side edges, a frame of substantially rectangular shape including a pair of rod members having one end bent to pivotally engage said shafts, a pair of bars spaced horizontally apart connecting said rods and extending parallel with the shafts, said frame being of a size to extend beyond the forward and rear portion of the liquid holding element, a handle rigidly secured between said bars, a spring sleeved on one said rod and having one end thereof engaging the plate member for retaining said element in parallel relation with the legs of the rod members of the frame when said element is not in contact with the surface to be cleaned, a clamping member rotatably secured to each said bar for movement away from said handle and around said absorbent compressible element to compress the same between the outer surfaces of said members, a spring member sleeved on one bar and a portion thereof sleeved on the other bar with the respective ends thereof engaging the outer surface of the respective clamping members for urging the clamping members toward said handle when the compressing action is completed, and latch means on said handle to hold said clamping members in engagement therewith.
